UNITED STATES PATENT OFFICE

2,606,534

OPERATING MECHANISM

Kenneth H. Pond, Longmeadow, Mass.

Application May 20, 1948, Serial No. 28,183

2 Claims. (Cl. 121—45)

1

This invention relates to improvements in an oscillating operating mechanism for oscillating a member back and forth.

The principal object of the invention is directed to the provision of an operating mechanism which is adapted to oscillate a member such as a shaft back and forth and is actuated by air pressure or the like. The mechanism is characterized by means for varying the speed of the member which is oscillated thereby.

The mechanism is adapted for various uses where it is desired to impart oscillations in opposite directions to a member.

As an example, the mechanism may be employed to oscillate the shaft of a drill press which actuates the quill to move the tool toward and into the work and away therefrom and according to novel features the mechanism operates to move the tool to the work at a high speed and then into the work at a relatively slow speed.

With the foregoing and various other novel features and advantages and other objects of my invention as will become more apparent as the description proceeds, the invention consists in certain novel features of construction and in the combination and arrangement of parts as will be hereinafter more particularly pointed out in the claims hereunto annexed and more fully described and referred to in connection with the accompanying drawings wherein:

Fig. 1 is a longitudinal sectional view through the operating mechanism of the invention;

Fig. 2 is an end elevational view of the mechanism shown in Fig. 1;

Fig. 3 is an elevational sectional view on the line 3—3 of Fig. 1; and

Figs. 4 and 5 are transverse sectional views on the lines 4—4 and 5—5 of Fig. 1.

Referring now to the drawings more in detail, the invention will be fully described.

A housing for the mechanism of the invention includes a forward end cap 2, a rear end cap 4, intermediate sections 6 and a ring 8. These members are secured together by screws or bolts 10 which may extend through marginal portions thereof.

A drive shaft 12 is rotatable in the housing and forward and rear glands 14 and 16 are provided in connection with suitable packings 18 and 20 for sealing the shaft 12.

The shaft 12 has a longitudinal bore 22 as shown and at one end receives a shaft 24 which is to be oscillated. This shaft 24 may be the shaft of a drill press for operating the quill thereof. A rod 26 has a lower threaded portion

2

28 in threaded engagement with shaft 12 and a pilot portion 30 in a suitable socket of shaft 24. By this means shafts 12 and 24 are held against relative rotation.

As will be seen, the ring 8 forms in connection with members 2 and an adjacent member 6 a circular chamber 32 while the member 4 is formed to cooperate with the other of the members 6 to form another chamber 34. These chambers are separate and may be called operating and control members respectively.

Packing 36 of suitable form is disposed around the shaft 12, as shown.

A propeller 40, see Figs. 1 and 5, has a tongue 42 which extends into shaft 12 so that the said shaft may be oscillated by the propeller. Cup packings 44 are secured to opposite faces of the propeller 40 and may be made from yieldable material as is usual and these engage the walls 20 of the chamber 32.

A partition 46 disposed in chamber 32 is fixed to member 8 by means of screws 48 or the like and it has cup packings 50 secured to opposite sides thereof.

Inlet ports 52 and 54 are provided in member 8 which lead into chamber 32 at opposite sides of partition 46.

The ports 52 and 54 will be connected to pressure means such as a pump or compressor for delivering fluid under pressure. Pressure control means such as valve means will be included in the pressure means so that pressure will be delivered to port 52 whereby the propeller will be moved counterclockwise and then pressure will be delivered to port 54 for moving the propeller clockwise. By applying pressure alternately to the ports the propeller is caused to oscillate back and forth in chamber 32.

Stops 56 extend from member 2 and rod 26 is adapted to bring up against these stops to limit movements of the shaft 12 as it is oscillated by the propeller.

A radially extending partition wall 60 is provided in control chamber 34 and a vane 62 is secured to shaft 12 by means of a screw or screws such as 64. A valve 66 has a stem 70 slidably extending through the vane 62 and a spring 71 around said stem 68 and disposed between the vane and a head 72 urges the valve to a position over ports 74 through the vane.

The chamber 34 is filled with oil or the like and as shaft 12 is oscillated by the propeller the vane is oscillated back and forth in the chamber 34.

A plug 80 is secured in the end of shaft 12 to

turn therewith and has a central bore 82. Ports 84 and 84' extend from the bore 82 through the plug and shaft 12 into chamber 34 at opposite sides of the vane 62.

A valve member 86 has a portion 88 in threaded engagement with the bore 82 of plug 80 and a conical end 90 adapted to engage a seat 92 at the inner end of bore 82.

As the shaft 12 and vane 62 move counterclockwise, oil in chamber 34 is forced to move through port 84 and out port 84' except as it is controlled by valve member 86. Communication between ports 84 and 84' is controlled by valve 86 and thereby the speed of movement of the shaft 12 counterclockwise may be varied according to the adjustment of valve 86.

As the shaft 12 and vane move clockwise, oil in chamber 34 between the vane and wall 60 passes through ports 74 and opens valve 66.

When the mechanism is used for operating the actuating shaft for the quill of a drill press, it is desired that the shaft 12 be moved counterclockwise at an initial speed which is greater than the final speed. This is to advance the tool to the work at a relatively high speed and then to advance the tool in the work at a relatively slower speed. This is accomplished by means to be described in connection with Figs. 1 and 3.

A plug 100 is provided in member 4 which has a bore 102 and a forward plate 104 secured to said member 4. Grooves 106 in the sides of plug 100 are provided which in conjunction with ports 108 provided passageways from the bore 102 to the chamber 34.

The plug 100 is so positioned with reference to wall 60 of chamber 34 that the grooves 106 are at opposite sides thereof. Thereby the bore 102 of the plug is in communication with the chamber at opposite sides of said wall 60.

A valve 110 is slidable in bore 102 of plug 100 and operates against a spring 112. When the valve is in inner position the ports 108 are closed off so that communication between bore 102 and chamber 34 is interrupted.

A cam plate 114 is provided which has a circumferential slot 116. Screws 118 extending through the slot 116 engage the end of shaft 12. By means of the screws and slot, the cam may be adjusted angularly relative to shaft 12.

A cam 118 on the plate is formed to engage the valve 110 as the shaft 12 oscillates counterclockwise and depress said valve and close off communication between bore 102 and chamber 34 or close communication between opposite sides of wall 60.

With a shaft such as 24 secured to shaft 12 and pressure delivered alternately to ports 52 and 54 of chamber 32, the propeller is acted upon to oscillate shaft 12 in opposite directions. Valve 86 is adjusted so that the desired speed of operation is attained. The cam 114 is adjusted so that valve 110 is operated thereby in such a manner that the shaft 12 as it is oscillated in one direction will operate at an initial speed which is relatively greater than the subsequent speed thereof.

The invention may be embodied in other specific forms without departing from the essential characteristics thereof. Hence, the present embodiments are therefore to be considered in all respects merely as being illustrative and not as being restrictive, the scope of the invention being indicated by the appended claims rather than by the foregoing description, and all modifications and variations as fall within the meaning and

purview and range of equivalency of the appended claims are therefore intended to be embraced therein.

What it is desired to claim and secure by Letters Patent of the United States is:

1. Fluid actuated operating mechanism for oscillating a member back and forth comprising in combination, a housing construction having separate aligned annular pressure and closed control chambers for fluid, a drive shaft oscillatable in said housing and disposed centrally of said chambers, said pressure chamber having a radially disposed wall fixed therein between said shaft and a side of said chamber, means limiting the angle of oscillation of said shaft, a propeller in said pressure chamber fixed to said shaft, said housing provided with inlets for fluid into said pressure chamber disposed adjacent and at opposite sides of said wall whereby fluid delivered alternately to said inlets acts on and oscillates said propeller and shaft in opposite directions, a radially disposed partition wall fixed in said control chamber disposed between said drive shaft and a side of said chamber providing opposite ends to said control chamber, a vane in said control chamber fixed to and oscillated by said shaft back and forth from one side of said partition wall to the other side thereof for displacing fluid in said chamber, said vane provided with a valved opening therethrough arranged and adapted as the vane is oscillated alternately in opposite directions to permit and prevent the flow of fluid therethrough, said shaft provided with passage means in communication with opposite ends of said control chamber for fluid displaced by said vane, and manually adjustable means operable in said passage means to vary the flow of fluid therethrough and the speed of oscillation of said vane, said housing construction provided with passage means in communication with opposite ends of said control chamber, a valve construction having a movable valve member in said last named passage means to close and open the same to prevent and permit the flow therethrough of fluid displaced by said vane and thereby in addition to the manually adjustable means to vary the speed of oscillation of said vane, and a member adjustable on said shaft for operatively engaging said valve member.

2. Fluid actuated operating mechanism for oscillating a member back and forth comprising in combination, a housing construction having separate aligned annular pressure and closed control chambers for fluid, a drive shaft oscillatable in said housing and disposed centrally of said chambers, said pressure chamber having a radially disposed wall fixed therein between said shaft and a side of said chamber, means limiting the angle of oscillation of said shaft, a propeller in said pressure chamber fixed to said shaft, said housing provided with inlets for fluid into said pressure chamber disposed adjacent and at opposite sides of said wall whereby fluid delivered alternately to said inlets acts on and oscillates said propeller and shaft in opposite directions, a radially disposed partition wall fixed in said control chamber disposed between said drive shaft and a side of said chamber providing opposite ends to said control chamber, a vane in said control chamber fixed to and oscillated by said shaft back and forth from one side of said partition wall to the other side thereof for displacing fluid in said chamber, said shaft provided with passage means in communication

with opposite ends of said control chamber for fluid displaced by said vane, and manually adjustable means operable in said passage means to vary the flow of fluid therethrough and the speed of oscillation of said vane, said housing construction provided with passage means in communication with opposite ends of said control chamber, a valve construction having a movable valve member in said last named passage means to close and open the same to prevent and permit the flow therethrough of fluid displaced by said vane and thereby in addition to the manually adjustable means to vary the speed of oscillation of said vane, and a member adjustable on said shaft for operatively engaging said valve member.
